CLAIM

The ornamental design for a rake cleaner attachment, as shown and described.

DESCRIPTION

FIG. 1 is a front elevational view of a rake cleaner attachment showing my new design;

FIG. 2 is a top plan view thereof;

FIG. 3 is a side elevational view thereof; the side opposite being a mirror image;

FIG. 4 is a rear elevational view thereof;

FIG. 5 is a side elevational view thereof; shown in the cleaning position; and

FIG. 6 is an enlarged perspective view thereof.

The broken-line showing of the rake head in the views is for illustrative purposes only and forms no part of the claimed design.
